Jonathan Clark of Hampton, Conn.
Seth's Patent

The subscriber resides on these Seth's Patent and making part of the same
containing a description in the name of which Jonathan Clark himself of
the Improvement in Cutting Potatoes into small bags. Many of More
-yeal & other regular & Cattle, to be used as Revolving Excellent Root Cutter.

To all People to whom these premises shall come Be it known that I Jonathan
Clark of Hampton in the County of New Haven State of Connecticut
having invented a new and useful Machine for Cutting Potatoes &c &c &c
Mangold. Turnip. Rutabaga & other Vegetables used for the feeding of Cattle
horses Sheep & all as well as for the cutting of Apples & other uses called the
revolving excellent root cutter and that the following is a full and exact de-
scription of the construction and operation of the sa Machine as invented by
me. This Machine for cutting Potatoes. Carrots. Rutabaga. Mangold. Turn-
ip and other Vegetables used for the feeding of Cattle horses Sheep &c &c
as well as for the cutting of Apples & other uses called the revolving excellent
root cutter is constructed in the following manner viz. It is supported by
a frame - one of a common size is about four feet long about one foot three
inches wide three feet high exclusive of the hopper which is ten inches
wide and six inches high exclusive of the hopper which is ten inches
wide six inches high six inches deep in back. Manure Ark contains a
revolving Cylindrical Disk or hollow about two feet in diameter
and about nine inches wide turned by Water. Stone or any other way
which may be found most convenient and the whole is back Machine
may be raised or lowered as the wants of the operator may require. The
description of the cylinder is attached one two or three cutting blades
placed diagonally or at right angles and the blades are cut in such a way
as most easily to cut vegetables or Apples &c &c &c &c &c &c &c &c &c &c &c &c
as required. This may be placed on the circumference of the cylinder
whence the Apples, Turnips & Rutabaga as may be wished the
frame of the cylinder may be made of any substance of sufficient strength

Time must be afforded by one half hour or otherwise a much more expensive
is as the Cost of labor is very high indeed, this is may have as much of a
biting time as the sweeping may require and often longer as may
exist. Consequently the cost of such a Cylinder may be made the
little less or more as the duration of said biting time may
require, when by hours or any other may such cylinder which by passing
time a cylinder the machine will come to be set to return to place in
the upper into such part as may be wished according to the placing of
the hand. The upper is constructed with a return to applied to it
slide or roll against the cylinder where it passes the time is coming
into place upper under the machine which reaches the same when
out. After a running of the time and cylinder is so constructed as
to be easily separated at the end for the application of the time. What
follows is my own invention & not previously known to the world or
anted machine to the application of time and return to a roller
which the said machine will cause rollers & other cylinders to be
put into use required in a much more expensive manner
and less labor than any other method I ever known. In testimony
that the above is a true specification of my said machine as above
described I have hereunto set my hand the 21st day of May A.D. 1833.
